UNITED STATES PATENT OFFICE.

REUBEN F. CORRY, OF RIVERTON, NEW JERSEY, ASSIGNOR TO UPLIFT PUBLISHING COMPANY, OF PHILADELPHIA, PENNSYLVANIA, A CORPORATION OF PENNSYLVANIA.

DESIGN FOR A LETTER-HEAD AS AN ARTICLE OF MANUFACTURE.

54,066.

Specification for Design.

Patented Nov. 4, 1919.

Application filed July 30, 1915. Serial No. 42,835. Term of patent 7 years.

To all whom it may concern:

Be it known that I, REUBEN F. CORRY, a citizen of the United States, and a resident of Riverton, Burlington county, New Jersey, have invented a new, original, and ornamental Design for a Letter-Head as an Article of Manufacture, of which the following is a specification, reference being had to the accompanying drawing, forming part thereof, in which the figure represents a fragment of a letter-sheet having my design for letter-head thereon.

I also contemplate using the design embodied in certificates, contracts, checks, notes, banking forms, identification cards or other similar articles of manufacture common in the arts.

I claim:

The ornamental design for a letter head as an article of manufacture, substantially as shown.

REUBEN F. CORRY.
